UNITED STATES PATENT OFFICE.

ARTHUR N. CROSS, OF MOUNT VERNON, NEW YORK.

ARTIFICIAL TOOTH.

Application filed June 1, 1923. Serial No. 642,742.

To all whom it may concern:

Be it known that I, ARTHUR N. CROSS, a citizen of the United States, residing at Mount Vernon, in the county of Westchester and State of New York, have invented certain new and useful Improvements in Artificial Teeth, of which the following is a specification.

My invention relates to artificial teeth and its objects are to provide an artificial tooth having means for locking the facing to the backing against relative movement in any and all directions so that a separation of the facing from the backing by pressure from any direction is practically impossible.

These objects, and other advantageous ends which will be described hereinafter, I attain in the following manner, reference being had to the accompanying drawing in which—

Figure 1 is a central section through a tooth constructed in accordance with my invention,

Figure 2 a section on line 2—2 of Figure 1,

Figure 3 a perspective view of the tooth facing shown in Figure 1, and

Figure 4 a perspective view of the backing shown in Figure 1.

Referring to the drawing, 1 indicates an artificial tooth composed of a facing 2 secured to a backing 3 by cement 4 or the like.

The facing 2, which may be made into any suitable shape and of any suitable white material, preferably porcelain, has a flat rear surface 5 provided with a vertical groove 6, a horizontally extending cavity 7 in the groove and a downwardly inclined rectangular cavity 8 at the lower end of the groove as shown in Figure 3.

The backing 3, preferably metallic, consists of a plate 9 having a vertical rib 10 adapted to fit into the vertical groove 6, a locking pin 11 projecting horizontally from rib 10 adapted to fit into the horizontally extending cavity 7, and a tongue 12 inclining downwardly from the bottom of rib 10 adapted to fit into the downwardly inclined cavity 8.

Rib 10 may be made integral with the plate or pressed therefrom as shown in Figure 4. Pin 11 is secured to the rib in any suitable manner such as by soldering, brazing or otherwise. The inclined tongue 12

is secured to plate 9 at the lower end of groove 6 by soldering or brazing. The cavities 7 and 8 are made slightly larger than the pin 11 and tongue 12, which they receive, so that the facing 2 may be easily applied to the backing without any binding action between the cavities and the pin and tongue.

When applying the facing 2 to the backing 3, the surface 5 of the facing is coated and the cavities filled in with cement 4. The facing is first held in the position shown in dot-and-dash lines in Figure 1, then slipped up into the position shown in full lines so that the vertical groove 6, horizontal cavity 7 and inclined cavity 8 will receive the vertical rib 10, the horizontally projecting locking pin 11 and the inclined tongue 12 respectively. The cavities 7 and 8, being slightly larger than the pin and tongue, readily permit this movement of the facing from the dot-and-dash line position to the full line position of Figure 1. The cement, filling the space left in the cavities and being between the surface 5 and plate 9, securely holds the facing to the plate.

In use, the rib 10 and the inclined tongue 12 prevent upward, lateral and turning movement of the facing 2 relatively to the backing 3 while the pin 11 locks the facing to the tongue 12 and the rib 10 by preventing downward movement of the facing relatively to the backing.

By constructing a tooth as above described, it is practically impossible to disconnect or separate the facing from the backing by pressure from any direction.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. An artificial tooth including a backing having a vertical rib and a horizontal pin projecting from the rib; a facing having corresponding cavities for receiving the rib and pin, and means for securing the facing to the backing.

2. An artificial tooth including a backing

having a vertical rib, a horizontally projecting pin and a downwardly inclined tongue; a facing having corresponding cavities for receiving the rib, pin and tongue, and means for securing the facing to the backing.

3. An artificial tooth including a backing having a vertical rib, a horizontal pin projecting from the rib and a downwardly inclined tongue at the bottom of the rib; a facing having corresponding cavities for receiving the rib, pin and tongue, and means for securing the facing to the backing.

4. An artificial tooth including a facing having a groove and a horizontal cavity extending from the groove; a backing having a rib and a horizontal pin adapted to take into the groove and cavity, and means for securing the facing to the backing.

5. An artificial tooth including a facing having a vertical rib, a horizontal pin projecting from the rib and a downwardly inclined tongue at the bottom of the rib; a facing having a vertical groove, a horizontal

tal cavity extending from the groove and a downwardly inclined cavity at the end of the groove for receiving the rib, pin and tongue, and means for securing the facing to the backing.

6. An artificial tooth including a backing having a vertical rib, a horizontal pin projecting from the rib and a downwardly inclined tongue at the bottom of the rib; a facing having a groove for receiving the rib, an inwardly extending cavity for receiving the pin, the cavity being of larger dimension than the pin, and a downwardly inclined cavity at the end of the groove for receiving the tongue, the inclined cavity being of larger dimension than the tongue, and means for securing the facing to the backing.

In testimony whereof I have signed my name to this specification in the presence of two subscribing witnesses.

ARTHUR N. CROSS.
